Primary Examiner — Paula Greene

CLAIM

The ornamental design for toilet seat handle lifting device, as shown and described.

DESCRIPTION

FIG. 1 is a front perspective view of a toilet seat handle lifting device showing our new design;

FIG. 2 is a front perspective view thereof;

FIG. 3 is a top perspective view thereof;

FIG. 4 is a bottom perspective view thereof;

FIG. 5 is a top plan view thereof;

FIG. 6 is a bottom plan view thereof;

FIG. 7 is a right side elevational view thereof; the left side elevational view is a mirror image;

FIG. 8 is a front elevational view thereof;

FIG. 9 is a rear elevational view thereof;

FIG. 10 is a perspective view thereof;

FIG. 11 is a perspective view in an alternate position; and,

FIG. 12 is a perspective view thereof.

The broken lines form no part of the claimed design.
